UNITED STATES PATENT OFFICE.

MAX E. CRANDALL, OF KINGFISHER, OKLAHOMA.

TOP.

1,123,697.

Specification of Letters Patent.

Patented Jan. 5, 1915.

Application filed April 11, 1913. Serial No. 760,511.

To all whom it may concern:

Be it known that I, MAX E. CRANDALL, citizen of the United States, residing at Kingfisher, in the county of Kingfisher and State of Oklahoma, have invented certain new and useful Improvements in Tops, of which the following is a specification.

This invention relates to spinning tops, and as one feature of novelty the invention 10 contemplates the provision of a top of double conical form provided at one apex with a sharply pointed plug or spindle and at its other apex with an approximately flat plug or spindle, the top being adapted 15 to be spun at the will of the user, in such manner as to strike the ground, either end foremost. As a result, the single top may be spun so as to be approximately stationary while spinning or may be spun so as to 20 "walk."

Another aim of the invention is to provide a top of double conical form, the two conical portions of which may be conveniently tapered so that the perimeter of the 25 top at the juncture of the bases of the conical portions will be located a greater or less distance above the surface upon which the top is spinning, depending upon which end of the top is in contact with the said surface 30 so that the top may be spun in such manner as to strike against and knock about other tops among which it is spun.

Another aim of the invention is to provide means for lightly gripping the knot 35 of the top string so that as the end of the string leaves the surface of the top an additional whipping effect will be produced causing the top to spin for a greater length of time and more rapidly than would otherwise be the case.

For a full understanding of the invention reference is to be had to the following description and accompanying drawing, in which—

Figure 1 illustrates a perspective view of the top immediately after it has left the top cord. Fig. 2 is a perspective view of the top. Fig. 3 is a side elevation of the top 45 illustrating in full lines its conical portions correspondingly tapered and in dotted lines the manner in which the taper of the two portions may be varied. Fig. 4 is a view partly in elevation and partly in section illustrating the manner in which the cord 50 is to be wound upon the top and the manner

in which the knot in the cord is to be engaged with the top.

Corresponding and like parts are referred to in the following description and indicated in all the views of the accompanying 60 drawing by the same reference characters.

The top embodying the present invention comprises essentially a body which is preferably formed from wood as in the instance of the ordinary type of top now on the 65 market and the said body is of double frusto conical form as clearly shown in the several figures of the drawing. One portion of the body is indicated specifically by the reference numeral 1 and the other conical portion by the reference numeral 2, the bases of the said portions being united at approximately the middle of the body as a whole, whereby to provide an intermediate peripheral portion 3 of greater diameter than any 70 other portion of the said body. While the conical portions 1 and 2 comprising the body of the top, may be tapered to the same degree as shown in full lines in Fig. 3 of the drawing, it may be found desirable and 75 very probably will, to give the two portions different degrees of taper, as for example, as shown in dot and dash lines in the said figure in which illustration the portion 1 is more gradually tapered than the portion 2, 80 and of course if desired, this relative proportionment of the two parts 1 and 2 of the body of the top may be reversed so that the part 2 will taper more gradually than 85 the part 1.

The portion 1 of the top body is provided at its apex with a plug or spindle 4 having a sharply pointed end 5, the said plug having the usual circumscribing groove 6 in which the top cord is placed prior to winding it upon the portion 1 which is of course, done in the usual manner. The portion 2 of the body is provided at its apex with a plug the shank of which is indicated by the numeral 7 and is provided with a head 8 the 90 striking surface of which is rounded as clearly shown in Figs. 2 and 3 of the drawing, but only to a slight degree so that the said face is nearly flat. The face is formed with a number of intersecting grooves 9 and 95 it will be readily understood that when the top is spun with this end as its striking end, the plug will by reason of its peculiar formation cause the top to "walk." It will be noted that the head 8 is slightly spaced from 100 105 110

the apex of the portion 2 so that a short length of the shank 7 is exposed and a groove is formed which corresponds to the groove 6 in the plug 4.

5 It will now be apparent that when the top is spun with the plug 4 as the striking plug, it will, after striking, remain approximately stationary while spinning, but on the other hand if it is so thrown that its plug 8
10 will strike, the top will, while spinning, move about from place to place which is of course desirable where the object is to strike other tops and roll them out of a ring. It will thus be seen that the top actually takes
15 the place of two tops, one provided with a sharp plug and the other with a blunt plug. Aside from the advantages gained by providing the top with two plugs different in form, the specific form of the plug head 8
20 constitutes an important feature of the invention. As above stated, a number of the grooves are provided and these grooves intersect each other so that when the top, while spinning, is inclined in one direction
25 or another the grooves will catch in the surface upon which the top is being spun and will cause the top to "walk" more rapidly than if the plug were merely of the ordinary blunt type.

30 It is a well-known fact that if in spinning a top a sharp pull is exerted upon the top cord after the top has left the hand, the top will be more rapidly spun and will remain spinning for a greater length of time but
35 skill is required to successfully whip the top as it leaves the cord.

The present invention has as one of its aims to provide a top which may be spun without the exercise of any particular skill
40 and which will spin as fast and as long as though not provided with the improvements embodying this invention but spun in an expert manner.

45 The means provided for accomplishing the above mentioned result, is in the nature of a recess or socket 10 which is formed in the peripheral portion 3 of the top at any desired point and which has extending from it at opposite sides and longitudinally of the top, relative shallow grooves 11 which re-

ceive the end portion of the top cord, the knot in the cord indicated at 12, being fitted in the socket 10. It will be understood of course that the walls of the recess 10 will lightly confine or engage with the knot 12
55 in the top cord so that as the top leaves the cord and the cord is whipped backwardly, additional momentum will be given the spinning top causing it to spin for a greater period of time than would otherwise be the case, although skill is not required to produce this result.

60 It will be observed by reference to Fig. 4 of the drawing that in winding the cord upon the top whether upon the portion 1 or
65 the portion 2 of the body thereof the knotted end of the cord is first engaged in the socket 10 and one of the grooves 11 and the cord is then laid beside the portion upon which it is to be wound, longitudinally of the top,
70 to the apex of the said portion where it is wound in the usual manner.

Having thus described the invention what is claimed as new is:—

1. A top comprising a body of substantially conical form, and a fixed spindle at the apex of the body, the said spindle being relatively blunt and formed with intersecting grooves.

2. A top comprising a body having the form of a double cone, and a fixed spindle at each apex of the body, the body at the juncture of the cones being formed with a knot-receiving socket and with cord-receiving grooves extending in opposite directions from the socket.

3. A top comprising a body of substantially conical form, and a spindle at the apex of the body, approximately semi-spherical and formed in its convex side with a plurality of intersecting grooves.

4. A top having a spindle provided with a plurality of separated bearing portions.

In testimony whereof I affix my signature in presence of two witnesses.

MAX E. CRANDALL. [L. S.]

Witnesses:

L. J. CONN,
B. M. HIPPARD.
